MATCH PACK HOLDER

Montague H. Duval, Great Neck, N. Y.

Application June 15, 1944, Serial No. 540,390

3 Claims. (Cl. 206—33)

1

This invention has to do with match pack holders.

It is designed primarily to receive the conventional paper match pack, but it is to be understood that it is adaptable to other or specially designed packs.

It has as its objects the provision of a holder which will completely house and protect the matches of the pack when not in use; from which the pack may be conveniently projected to permit removal of a match; the provision of means for automatically controlling the relation of the pack to the holder after it has been projected and upon release of the projecting means; a construction in which the ignition surface of the pack is conveniently accessible for lighting a match only after the pack has been returned to housed position within the holder, and which is so fashioned that the pack may be conveniently inserted in the holder, the conventional cover flap removed, and the pack stub and splints held against displacement when a match is pulled off, but from which the stub of a used pack may be conveniently and quickly removed to permit reloading.

Other objects will appear in the detailed description which follows:

In the drawings herewith, forming a part of this disclosure, embodiments of the invention are shown, and these the best now known to me, but it will be understood that these are illustrative and in no sense restrictive of the invention, as it may be developed in equivalent forms and still be within the purview of the invention.

In the drawings:

Figure 1 is a view in front elevation of the holder.

Figure 2 is an elevation showing the closed side of the holder.

Figure 3 is an elevation showing the open side of the holder.

Figure 4 is a rear view of the holder.

Figure 5 is a view showing the clip for the match pack projected from the holder for removal of a match.

Figure 6 is a view, a portion only of the holder being shown in horizontal position, with the clip and pack fully projected.

Figure 7 is a plan view of the pack holding clip.

Figure 8 is a section on substantially line 8—8 of Figure 7.

Figure 9 is an end view of the clip.

Figure 10 is a view of the opposite end of the clip.

2

Figure 11 is a sectional view on substantially the line 11—11 of Figure 8.

Figure 12 is a sectional view showing a portion of the holder in horizontal position and the manner of inserting the match pack in the clip.

Figure 13 is a similar view showing the match pack completely inserted in the clip.

Figure 14 is a side view of a modified form of clip.

10 Figure 15 is a front view of a modified form of holder.

Figure 16 is an edge view of the closed end of the holder shown in Fig. 15.

15 Figure 17 is a view in elevation of the open side of the holder shown in Figure 15.

Figure 18 is a view of the back of the holder showing the modified form of manually engageable means.

20 Figure 19 is a view showing a portion of the housing in horizontal position with the clip fully projected and latched in such position.

Figure 20 shows the clip partially projected from the housing for the removal of a match.

25 Figure 21 is a sectional view substantially on the line 21—21 of Figure 18.

Figure 22 is a view in elevation of a modified form of match pack clip.

Figure 23 is a view in elevation of the clip shown in Figure 22.

30 Figure 24 is a view in elevation of the opposite end of the clip.

Figure 25 is a view in elevation of the rear of the modified form of clip.

Figure 26 is a perspective view of the clip.

35 Figure 27 is a perspective view of another form of pack and clip.

In the description which follows, like reference numerals are applied to like parts in the several views.

40 The holder comprises the housing 10, which may be formed of any suitable material, such as metal or plastic compositions. Light gauge metal, die cast, stamped, or otherwise shaped is one material which is well adapted to the purpose.

45 The housing 10 has at least one open side 11, and the front and back wall 12 and 13. Preferably, the side 14 will be closed so that there will be a complete housing of the match pack within the holder ensuring protection for the ignitable match splints. One of the walls, here shown as the front wall 12, has an aperture 15 open at one end so as to offer no obstruction to the striking of a match, disposed at a convenient point therein, preferably at or near the

50 lower end of the wall 12. The aperture 15 will

register with the ignition surface of the pack, which is usually at the bottom of the pack on the stub portion, when the pack is housed within the holder and provides a striking aperture through which a match may be struck on the ignition surface.

Movably mounted in the housing 10 is the pack holder or clip 16, here shown as mounted on a pivot 17 disposed at a convenient point of the clip 16 and about which pivot 17 the clip 16 and its contained match pack may be swung. As here shown, the pivot pin 17 passes through a projecting bottom portion of clip 16. The clip 16, as here shown, will be provided with a projection 18 on its face, here shown as the rear face, which projection 18 will clear the back wall 13 so that it may be manually engaged by the fingers of the user and the clip 16 and its contained pack projected outwardly through the open side 11, as shown in Figures 3 and 4. In order that the holder may be readily manipulated in one hand and the clip 16 and pack projected, it is preferable to provide the front wall 12 of the holder with a roughened surface 19 which will form an area for engagement of the thumb of the user. This thumb engageable surface 19 on the front wall 12, together with the grip of the fingers on the back 13, in position to engage the projection 18 on the clip 16, give a very convenient and natural relation of the hand of the user to the device for operating it. The area 19 for thumb engagement may be formed in any convenient manner and may take the form of ornamentations, as shown, so disposed relative to one another as to provide a proper engaging surface for the ball of the thumb and prevent slippage on the otherwise smooth surface of the front wall 12.

Projection of the clip 16 and the pack through the open side 11 of the housing 10 will be controlled by a relatively light spring. As shown here, in Figs. 1, 5, 6, 12 and 13, this takes the form of a leaf spring secured in the bottom of the holder, and arranged to cooperate with clip 16 so that it tends to retain the clip within the housing. It will be seen, however, that reversal or variation of the spring action may be provided for, if such design were desirable in certain forms of the invention. As here shown, when the projection 18 is engaged by the finger and the holder and pack moved out of the housing to permit a match to be pulled off, the spring 20 will be under tension, and, on release of the clip 16, will at once automatically move it back into the housing 10, bringing the ignition surface of the pack into registry with aperture 15 to permit the striking of a match, the rest of the matches being then completely housed and guarded against accidental ignition.

It will be seen that when the clip 16 and pack are projected to the position shown in Fig. 5 to permit a match to be pulled off, the ignition area of the pack is substantially inaccessible, as it lies behind the wall portion 21 of the front wall 12 so that striking of a match on the ignition surface when the splints of the pack are exposed cannot be conveniently done because of the blocking of the ignition surface by the wall portion 21.

The clip 16 will be moved out of and returned to the housing 10 in the manner described and the matches pulled off until the entire pack is consumed and pack replacement becomes necessary. When replacement is to be made the clip 16 will be pushed out of the housing 10 to the

position shown in Figs. 6, 12 and 13, in which position the spring 20 will snap past the corner 22 of the clip 16 and hold the clip 16 in its outer position ready for refilling with a fresh pack. It will be seen that spring 20 has, as here shown, two functions. It resists projection of the clip 16 and pack as it is moved partially out of housing 10 for the pulling off of a match and automatically returns them on manual release of the holder. When the clip is fully projected for pack renewal, it maintains the clip 16 and stripped pack stub in convenient position for pack stub removal and reloading, its position being then such that endwise movement of the used stub to free same from the clip can be readily accomplished.

The clip 16 has the wall 23 and the apertured wall 24, the aperture in wall 24 registering with the ignition surface of the pack when it is in position, and with the aperture 15 in the wall 12 of housing 10 when the clip 16 and pack are housed.

It is most desirable that this aperture have at least one end completely open, so that in striking a match, same may be drawn straight over the striking surface without danger of the match head catching on any projection. In order to achieve this feature, and still give adequate strength to the top portion of apertured wall 24, a bridge 26 is provided between walls 23 and 24. In addition to the purpose already mentioned, this bridge also acts as a stop for the match pack when a new pack is inserted, since the splints engage against same, as clearly shown in Fig. 12. The end of clip 16 opposite bridge 26 is provided with a short wall 25 in its lower portion, such that a pocket is formed inside the clip, between the bottom of the clip proper and this wall 25. When the match pack stub is engaged in final position in the clip, it rests upon the bottom of same, and is prevented from endwise movement as matches are removed from the stub, by virtue of wall 25 in one direction and by bridge 26 in the other direction.

To prevent vertical movement of the pack in the holder the wall 23 is provided with an inwardly turned edge 27 which serves as a tearing edge for the covering flap of the pack. The position of this tearing edge in relationship to the upper edge of wall 25 is such that when a fresh pack is slid endwise into the clip, a predetermined portion of the back flap of the pack is spaced off, that is, a portion equal to the distance between the top edge of wall 25 and the tearing edge 27. After the remainder of the back flap has been removed, in a manner to be subsequently described, it will be seen that the portion of the back remaining attached to the pack stub may be pushed downwardly, so that its upper edge engages under the turned-in edge 27, as shown in Fig. 13. Thus, the pack stub is prevented from upward movement by being positioned beneath edge 27, and from endwise movement as previously described. When the match splints have been removed, however, the used stub will clear bridge 26 and can be pushed horizontally out of clip 16 and a fresh pack inserted.

In the form shown in Figs. 8 and 10, the inwardly bent edge 27 of the wall 23 is serrated or sharpened to form a scoring edge, and such scoring edge will indent or partially sever the covering flap of the pack so as to render its removal by tearing an easy matter.

The method of inserting a match pack into the clip is shown in Figs. 12 and 13. As the fresh

pack is slid in over the top edge of wall 25, the used stub is pushed out at the opposite end. Since all splints have been removed from the used stub, such stub will now pass readily under the bridge 26. Bridge 26 may be provided with a sharpened inner edge 26', in which case partial severance of the edge of undesired portion of the back flap will be commenced when the pack is inserted to the point shown in Fig. 12. It will be noted that the new match pack is now resting on the upper edge of wall 25. The undesired portion of the back flap, that is, the portion not contained within the limits bounded by top of wall 25 and tearing edge 27, is now torn off, the edge 27 providing a convenient and firm line against which the tearing may be done. The match pack stub is then pushed inwardly and downward, to the position shown in Fig. 13. It will be noted that the stub is now locked securely in the pocket formed by wall 25 and the bottom of the clip. Upward and endwise movement are restricted as heretofore described. When all match splints have been removed, the operation may be repeated, the used stub pushed out under bridge 26, and the clip re-loaded with a fresh pack.

In Figs. 15 to 21, inclusive, is shown a slightly different construction, although embodying the same mechanical principles. The housing 29 and holder 35 are substantially the same, except that the projection 31 on the holder is extended to provide a plurality of finger pieces 32, a slot 33 being provided in the rear wall 34 of the housing to permit movement of the fingers.

In this form of the invention the clip 35 will be pivoted at 36, and a spring 37 mounted on the pivot 36 with one end anchored beneath the pin 38 and the other end engaging the bottom of the clip, as shown in Figs. 18, 19, and 20. The return of the clip from its partially projected position, as shown in Fig. 20, will be effected automatically by the spring 37 as in the construction heretofore described.

In order to hold the clip and pack in fully projected position, as shown in Fig. 19, there is provided a latch 40, formed of spring metal and secured to the clip 35 at 41 in any suitable manner, here shown as soldered in place, although it may be otherwise secured, or formed integral with the metal of the clip. The latch 40 has a projection 42, which, when the clip 35 takes the position shown in Fig. 19, engages the bottom of the holder and maintains the clip 35 in fully projected position and holds it there for reloading. When latch 40 is pressed inwardly to release projection 42, spring 37 will return clip 35 and its pack to the housing.

In Figs. 22 to 26, inclusive, is shown a clip differing from the clip just described. This clip has the pocket 43 for holding match splints and has on opposite sides of the splints the leaves 44 which extend above and are bent inwardly over the match heads. These leaves 44 may be made of flexible cardboard or metal, so as to form spring walls which may be spread to give access to the splints and permit pulling them from the stub, after which they will spring into place.

The lower portion of this clip will be used exactly as in the forms previously described. Insertion of the match pack will be made by sliding the pack into the clip through the open side (shown in Fig. 24). The stub of used pack will be pushed out under bridge 46, and flap of fresh pack will be scored by inturned and sharpened lugs 53. When fully inserted, the lower portion of the holder is grasped firmly to hold stub in

place, and the undesired portion of the flap is torn off at the line created by lugs 53. Thereafter the pack is pushed inwardly and downward, so that the stub locks inside wall 45, and under bridge 46 and lugs 53, in similar manner to forms previously described.

The construction of this clip is such that it forms a complete match pack carrier and is capable of use independently of the holder, if desired. It provides a pack carrier in which the conventional match pack may be readily mounted; its construction is such that the splints are at all times completely protected, and the matches may be readily removed, as needed, from between the resilient protecting leaves.

In Figure 27 is shown a slightly different form of clip. It may be formed of any suitable material, as, for example, paper or cardboard of proper strength and resiliency. One convenient method of forming the clip shown in Figure 27 is to fold a strip of material 54 so as to provide at its lower end a pack receiving portion in which the match pack 55 will be inserted. From this pack receiving portion 54 the integral spring leaves 56 extend upwardly so as to embrace the match splints. At their upper ends the leaves 56 are preferably bent inwardly at 57 so as to cover the heads of the match splints. The leaves 56 will have sufficient resiliency to normally enclose the match splints, but may be readily separated in order to permit match removal. To facilitate separation of the leaves 56 the corners 58 of the inwardly turned upper ends 57 are preferably rounded so that they may be easily wedged apart and the leaves separated for access to the matches.

It is obvious that structural variations, exercising only mechanical skill, may be made from the illustrative examples of the invention herein disclosed, and all such changes are to be regarded as within the range of my invention as expressed in the appended claims.

I claim:

1. An open top match pack clip having a bottom, pack embracing side walls, and open ends to permit a pack to be slid longitudinally into place between said side walls, said pack including a stub and splints removably connected thereto at points defining a tearing line; a short stub-retaining wall projecting upwardly from the bottom at one of the open ends of said clip to engage a pack stub after a pack has been inserted and prevent reverse sliding movement and removal of a pack from the clip, and a splint-engaging bridge at the opposite open end of said clip extending between said side walls to engage and limit forward sliding of a pack and prevent forward movement and removal of the pack from the clip until the splints have been removed, said opposite open end being otherwise unobstructed, said bridge being disposed entirely above the tearing lines of the splints of said pack.

2. An open top match pack clip having a bottom, pack embracing side walls, and open ends to permit a pack to be slid longitudinally into place between said side walls, said pack including a stub and splints removably connected thereto at points defining a tearing line; retaining means on one of said side walls to engage a match pack and prevent vertical movement of the pack; a short stub-retaining wall projecting upwardly from the bottom at one of the open ends of said clip to engage a pack stub after a pack has been inserted and prevent reverse sliding movement and removal of a pack from the clip, and a splint-

engaging bridge at the opposite open end of said clip extending between said side walls to engage and limit forward sliding of a pack and prevent forward movement and removal of the pack from the clip until the splints have been removed, said opposite open end being otherwise unobstructed, said bridge being disposed entirely above the tearing line of the splints of said pack.

3. A match pack holder comprising a housing having an open side; a pack holding clip pivotally mounted in said housing and having a bottom, pack-embracing side walls, and open ends to permit a pack to be slid longitudinally into place between said side walls, said pack including a stub and splints removably connected thereto at points defining a tearing line; a short stub-retaining wall projecting upwardly from the clip bottom at one of the open ends of said clip to engage a pack stub and prevent reverse sliding movement and removal of a pack from the clip; a splint-engaging bridge at the opposite open end of the clip extending between said side walls to engage and prevent removal of the pack from the clip until the splints have been removed, said opposite open end of the clip being otherwise unobstructed, said bridge being disposed entirely above the tearing line of the splints of said pack; manually op-

erable means to project said clip through the open side of said housing, and a spring automatically to return said clip to said housing on release of said manual projecting means.

MONTAGUE H. DUVAL.
